UNITED STATES PATENT OFFICE.

CHARLES E. BARBER, OF SYRACUSE, NEW YORK.

BOAT-PROPELLER.

No. 812,475.

Specification of Letters Patent.

Patented Feb. 13, 1906.

Application filed April 1, 1905. Serial No. 253,216.

To all whom it may concern:

Be it known that I, CHARLES E. BARBER, of Syracuse, in the county of Onondaga, in the State of New York, have invented new and useful Improvements in Boat-Propellers, of which the following, taken in connection with the accompanying drawings, is a full, clear, and exact description.

This invention pertains to steamboats and other power-driven vessels in which the propelling device consists of a longitudinally-disposed shaft which is rotated by the engine or motor and a set of radially-projecting blades secured to said shaft. It is well known to persons familiar with this class of boats that in order to drive the same rearward it requires either a reversal of the engine or employment of certain connections between the engine-shaft and propeller-shaft operative for imparting a backward rotation to the latter.

The main object of the present invention is to provide a propeller of the aforesaid type which shall permit of quick and convenient regulation to effect either a forward or rearward drive of the boat, thereby obviating the necessity of reversing the rotation of the propeller-shaft.

Another object of the invention is to produce a propeller which shall be simple, strong, and durable in construction, efficient in its operation, and at the same time easily controlled.

To that end the invention consists in the novel arrangement and combination of the component parts of the propeller, as herein-after fully described, and set forth in the claims.

In the accompanying drawings, Figure 1 is a plan view of a boat-propeller embodying my invention and showing the parts in position for driving forward. Fig. 2 is a side view of the same in condition for driving a boat rearward. Fig. 3 is an enlarged rear view of the propeller-wheel minus the removable section of its hollow hub and showing the devices for axially turning the blades to set the same in either propelling or reversing positions. Fig. 4 is an enlarged longitudinal section of said hub and showing the connections between the longitudinally-shifting actuating-sleeve and the devices which turn the blades. Fig. 5 is a transverse section taken on the dotted line X X in Fig. 4. Fig. 6 is an enlarged perspective view of the longitudinally-sliding studded block which engages the slotted piv-

oted portions of the blades, whereby the latter are axially turned. Fig. 7 is an enlarged side view of the inner end portion of one of the blades, and Fig. 8 is an end view of said blade and showing the slotted collar formed thereon.

Referring to the said drawings, A denotes the propeller-shaft which is to be connected to the shaft of the engine or motor by any suitable or well-known means which shall sustain the former against endwise movement and is designed to be rotated in only one direction, which connection is not illustrated, as it does not pertain to the invention. It is understood that this shaft A is to extend lengthwise the boat and supported in the usual manner.

B denotes the propeller-wheel, which comprises a hollow spherical hub a and a set of radially-disposed blades b b b, pivotally secured to said hub, as will be hereinafter described. The said hub a is formed with a tubular portion c, which embraces a rearwardly-tapering portion d of the shaft A and is permanently fastened thereto, preferably by means of a key e, as clearly shown in Figs. 4 and 5 of the drawings. The hub is transversely divided to form two sections a' a', the outer section a' being secured removable on the shaft by means of a nut f applied to the screw-threaded end of said shaft. To prevent this section from becoming accidentally loose, I provide the shaft with a jam-nut g and cotter-pin h. The shaft is reduced circumferentially from its tapered portion to the end to accommodate the ends of the blades and the device for axially turning the same, which device will be shortly explained.

The hub is provided with radially-disposed annular openings i i at the line of division and formed with annular exterior bearing-surfaces j j j, surrounding the opening, which surfaces are provided with rabbets k k k, as shown in Figs. 3 and 4 of the drawings. Each of the aforesaid blades b is formed with a short stem l at its inner end, by which it is pivoted in the opening i and formed with a shoulder m, abutting against the bearing-surface j and seated in the rabbet k. Each of the said stems l is formed with a collar n, preferably elongated transversely at one side and provided with a transverse slot o, these collars abutting against similar bearing-surfaces p p p, formed on the interior of the hub, and serve to hold the blades in the hub. By this arrangement and construction the blades can

be independently attached to and detached from the hub by removing the section a^2 of said hub, as clearly illustrated in Fig. 3 of the drawings.

5. C represents a block which is preferably of triangular shape and formed with an aperture b^2 , by which it slides longitudinally upon the shaft A within the hub. This block is formed on its edges with studs $b' b' b'$, disposed parallel to the axes of the blades, and which engage the slots $o o o$ in the collars thereof. By this engagement of the studs and slots the blades are turned axially when the said block is shifted back and forth on the shaft, thereby adjusting the blades to either propelling or reversing position. The said block is actuated by means of longitudinally-movable rods $c' c' c'$, which slide in guides $d' d' d'$, formed in the tubular portion c of the hub B. The rear ends of the rods are screw-threaded and pass through the block and are provided with nuts $e' e' e'$, which rigidly secure the block thereto, said block being shouldered on the rods, as indicated at f' .
25. The forward ends of the said rods are also screw-threaded, and thereby secured to a collar D, which is mounted longitudinally movable on the shaft A and adapted to abut against the end of the tubular portion of the hub when shifted rearward to turn the blades to propelling positions, as shown in Figs. 1 and 4 of the drawings.

35. A' represents a longitudinally-movable sleeve which embraces the shaft A and serves to shift the collar back and forth on the shaft, and thereby actuate the aforesaid block C. The collar is preferably secured to the sleeve by screw-threading the parts, as shown in Fig. 4 of the drawings.

40. It will be observed that by loosening the nuts $e' e' e'$ the rods $c' c' c'$ can be turned so as to adjust the block C in relation to the collar D, and thereby regulate the turning of the blades, and thus any desired speed of a boat 45 may be attained, either forward or backward.

50. B' is an upright hand-lever which may be arranged in any suitable and convenient manner to be operated by the person in charge of the engine and which is employed for shifting the sleeve A'. I prefer, however, to bifurcate the lower portion of said lever to accommodate the shaft A and pivot the same to a suitable bracket C', fastened to the engine or other support, as indicated at D'. Said lever is connected to the sleeve by means of links or bars $g' g'$ and a collar h' , rigidly embracing the inner end of the sleeve, as shown in Figs. 1 and 2 of the drawings.

What I claim is—

60. 1. In a boat-propeller, the combination of a rotary shaft suitably sustained against endwise movement, a propeller-wheel comprising a hollow hub mounted on said shaft and a plurality of radially-disposed blades pivotally and detachably secured to said hub, a

block sliding longitudinally on the shaft within the hub for turning the blades to either propelling or reversing positions, a longitudinally-shiftable sleeve embracing the shaft, means adjustably connecting the block to said sleeve and transmitting motion from the latter to said block, and means for shifting said sleeve as set forth.

2. In a boat-propeller, the combination of a rotary shaft suitably sustained against endwise movement, a propeller-wheel comprising a transversely-divided hollow hub having the shaft extending beyond the same and provided with radial openings at the line of division, and blades detachably and pivotally secured in said openings, the inner section of the hub being permanently secured to the shaft and the outer section removably secured thereon, a block sliding longitudinally on the shaft within the hub and provided with projections engaging the blades for turning the latter to either propelling or reversing positions, a longitudinally-shiftable sleeve embracing the shaft in front of the hub, adjustable means for transmitting motion from the sleeve to the block, and means for shifting the sleeve as set forth.

3. In a boat-propeller, the combination of a rotary longitudinally-disposed shaft suitably sustained against endwise movement, a propeller-wheel comprising a hollow hub mounted on the shaft and divided transversely to form two sections and provided with a plurality of radial openings at the line of division, and blades pivotally and detachably secured in said openings, the inner hub-section being permanently fastened to the shaft and provided with a series of longitudinal guides, and the outer hub-section secured removably on the shaft, a block sliding longitudinally on the shaft within the hub and provided with means for turning the blades axially to either propelling or reversing positions, a longitudinally-shiftable sleeve embracing the shaft independent of the hub, and rods extending through the aforesaid guides and adjustably connecting the block to the sleeve and transmitting motion from the latter to the block, and means for shifting said sleeve as set forth.

4. In a boat-propeller, the combination of a longitudinally-disposed rotary shaft suitably sustained against endwise movement and having its rear end screw-threaded, a propeller-wheel comprising a hollow hub provided with a plurality of radial openings and divided transversely on a line diametrically through the openings, the inner section being permanently secured to the shaft and the outer secured removably thereon and having the threaded portion of the shaft projecting therefrom, a nut on said shaft and sustaining the outer section in its position, and blades formed with stems by which they are pivotally and detachably secured in the aforesaid

openings and provided with bearing-surfaces formed on the exterior and interior of the hub, a longitudinally-sliding block on the shaft within the hub and engaging the stems of the blades, means for adjusting the block to regulate the movement of the blades, and means for actuating said block as set forth.

5. In a boat-propeller, the combination of a rotary shaft sustained against endwise movement, a propeller-wheel comprising a hollow hub divided transversely to form inner and outer sections, the inner section being formed with a tubular portion by which it is permanently secured to the shaft, and the outer section being removably secured thereto, longitudinal guides in said tubular portion, a triangular block provided with a central aperture by which it slides longitudi-

nally on the shaft within the hub and provided with additional apertures at the corner portions thereof, a longitudinally-shiftable sleeve embracing the shaft and formed with a collar adapted to abut against the tubular portion of the hub, rods passing through the aforesaid guides and having their rear ends screw-threaded and extending through the corner apertures of the block, nuts on said rear ends of the rods, the opposite ends of the rods being screw-threaded and fastened to the said collar, and means for shifting said sleeve as set forth.

CHARLES E. BARBER.
